CLAIM

The ornamental design for a hollow plastic handle for squeeze-dispensing shaving cream to a removable razor head, as shown and described.

DESCRIPTION

FIG. 1 is a perspective top and side view of a hollow plastic handle for squeeze-dispensing shaving cream to a removable razor head, showing my new design, and shown in association with a removable razor head shown in phantom outline and not a part of this invention;
FIG. 2 is a side view thereof, the unshown opposite side being of mirror image appearance;
FIG. 3 is a front view thereof;
FIG. 4 is a rear view thereof; and,
FIG. 5 is a top view thereof.
